E. W. MYERS.
APPARATUS FOR SYNCHRONIZING MUSIC AND MOTION PICTURES.
APPLICATION FILED AUG. 21, 1916.

1,261,272.

Patented Apr. 2, 1918.

UNITED STATES PATENT OFFICE.

EDGAR WM. MYERS, OF LOS GATOS, CALIFORNIA, ASSIGNOR TO MASTERROLL PERFORATING MACHINE COMPANY, OF SAN FRANCISCO, CALIFORNIA, A CORPORATION OF CALIFORNIA

APPARATUS FOR SYNCHRONIZING MUSIC AND MOTION-PICTURES.

1,261,272.

Specification of Letters Patent.

Patented Apr. 2, 1918.

Application filed August 21, 1916. Serial No. 116,126.

To all whom it may concern:

Be it known that I, EDGAR W. MYERS, a citizen of the United States, and resident of Los Gatos, in the county of Santa Clara, and in the State of California, have invented a certain new and useful Improvement in Apparatus for Synchronizing Music and Motion-Pictures, and do hereby declare that the following is a full, clear, and exact description thereof.

The object of my invention is to secure accurate registry or synchronism of the exhibition or display of moving pictures and the musical accompaniment thereof so that the display of the pictures and the rendition of the music will be in correct relation. The musical accompaniment, may, as is customary, be either a piano or other key-operated instrument or an orchestra. For the attainment of this object and also the attainment of the object by the simple and efficient mechanism, my invention consists in apparatus having the characteristics of construction and function substantially as hereinafter specified and claimed.

In the accompanying drawings is illustrated apparatus embodying one form of my invention, and in such drawings—

Figure 1 is a view partly in elevation and partly in perspective of such apparatus;

Fig. 2 is a view partly in section and partly in side elevation of the circuit-closing device shown in Fig. 1;

Fig. 3 is a view similar to Fig. 1 illustrating apparatus embodying the invention for the production of a master roll.

Briefly described, my invention comprehends the operative association or connection with the projector machine of moving picture apparatus of a device for producing at regular and comparatively short intervals a signal, or indicating means for the musician whereby he is enabled to cause the rendition of the music in accurate time relation with the picture being exhibited. In what I now conceive the best form of my invention such signal is an electric light which is at the desired intervals cut into and out of circuit and which light is located to be conveniently available to the musician and the turning on of which is in a predetermined relation to arbitrary marks, such as stars, placed upon the perforated music roll, if a mechanical player instrument is being em-

ployed, or upon the musical score or sheet 5 if the accompaniment is by an orchestra.

A portion of a moving projector machine 10 is shown in the drawing and to the main shaft 11 thereof I connect one end of a flexible shaft, or cable 12 whose other end is 60 connected with a shaft 13 of a conveniently located circuit opening and closing device 14 that is in circuit with an electric lamp 15, which in Fig. 1 of the drawings is shown mounted at the left of the tracker board of 65 a mechanical piano player 16. Preferably the connection between the flexible shaft 12 and the shaft 13 is by means of a detachable coupling 17. The shaft 13 is journaled in 70 bearings in the frame or casing of the device 14, and it has a worm 18 which meshes with a worm wheel 19, the worm gearing being so proportioned in the case shown as to cause one revolution of the worm wheel 19 for 75 sixty turns of the operating crank of the projector machine. Of course, I do not limit myself to any particular proportions. I mention the proportions stated simply by way of illustration. The worm wheel 19 carries on its side a circular series of equally 80 spaced projections 20, which, as shown, are rollers and are four in number, and in the path of revolution of these projections is a spring contact finger 21, which, by the action of each roller thereon is pressed against 85 a stationary contact finger 22, and the respective fingers being in circuit with the lamp 15, the coming together of the two fingers closes the circuit through the lamp and lights it. As soon as the roller passes 90 out of contact with the spring finger the circuit is automatically broken. It will, therefore, be seen in the proportion of gearing shown and with the four rollers the lamp will be lighted once every fifteen seconds. 95 On the left margin of the perforated music sheet 23, adjacent the lamp 15 and at regular intervals apart, I place a series of stars 24, or other arbitrary marks, which, by the travel 100 of the perforated sheet are brought in succession adjacent the lamp, at the time the lamp is lighted. The piano operator, therefore, is able to cause the musical accompaniment accurately to register with the projection of the picture on the screen. 105

For the production of the master roll, in place of operating a light by the closing and opening of the circuit by means of the device

14, I operate a punch that makes regularly, or uniformly spaced holes in the margin of the master roll. Thus from these marginal perforations in the master roll the duplicate 5 player operating rolls made therefrom are provided with the star, or other indicating device, for coöperating with the electric lamp. An apparatus for providing the punches in the master roll is illustrated in 10 Fig. 3, which, as shown, is the punching mechanism forming the subject of my United States application for Patent No. 875338 filed Dec. 3, 1914, the wires from the circuit closing device being run to a magnet 25 15 which controls the operation of the star producing punch.

In preparing sheet music for an orchestra, the score is written from the roll and the 20 marks on the sheet music coöperating with the lamp are placed on the music. In the use of sheet music the lamp is mounted on the music holding stand.

Having thus described my invention what I claim is—

25 1. The combination of motion picture exhibiting means, a signal producing device, a music sheet having indicia at selected points with which the signal produced by said signal-producing device has a coöperative 30 relation, and means for periodically operating the signal, operatively connected with said picture exhibiting means.

35 2. The combination of motion picture exhibiting means, a signal producing device, means for periodically operating the signal, operatively connected with said picture exhibiting means, and a music sheet having a series of indicia coöperating with said signal in succession.

3. The combination of a motion picture 40 projecting machine, a signal producing device, a music sheet having indicia at selected points with which the signal produced by said signal-producing device has a coöperative relation, and means for periodically 45 operating the latter, operatively connected with said machine.

4. The combination of a motion picture projecting machine, a signal producing device, a music sheet having indicia at selected 50 points with which the signal produced by said signal-producing device has a coöperative relation, and means for periodically operating the latter, operatively connected with said machine, and comprising a circuit closing and opening device.

5. The combination of a rotating shaft of a motion picture projecting machine, a signal producing device, a music sheet having 60 indicia at selected points with which the signal produced by said signal-producing device has a coöperative relation, means for periodically operating the latter, comprising a shaft-actuated circuit closer, and an operative connection between such shaft and the 65 shaft of the projecting machine.

6. The combination of a motion picture exhibiting machine, a musical instrument, a perforated sheet for actuating said instrument, indicia on said sheet, a signal having a coöperative relation with said indicia, a signal-actuating device, and means for periodically operating said device operatively connected with said picture exhibiting machine.

In testimony that I claim the foregoing I have hereunto set my hand.

EDGAR WM. MYERS.
